MOTORCYCLE SADDLEBAG COVER

John L. Marchello, Ann Arbor, Mich., assignor to Joseph Buegeleisen Co., Southfield, Mich.

Filed Feb. 19, 1964, Ser. No. 78,689

Term of patent 14 years

(Cl. D90—3)

FIG. 1 is a plan view of a motorcycle saddlebag cover showing my new design.

FIG. 2 is an elevational view thereof;

FIG. 3 is a rear end view thereof.

FIG. 4 is a front view thereof.

The saddlebag shown in broken lines in FIGS. 2, 3 and 4 is included for illustrative purposes only.

I claim:

The ornamental design for a motorcycle saddlebag cover, as shown and described.
